DESIGN FOR A COMBINED DOOR LATCH HANDLE AND MOUNTING FOR REFRIG- ERATORS OR THE LIKE

John R. Morgan, Oak Park, Ill., assignor to Sun-
beam Electric Manufacturing Co., Evansville,
Ind., a corporation of Indiana

Application December 22, 1939, Serial No. 89,093

Term of patent 3½ years

To all whom it may concern:

Be it known that I, John R. Morgan, a citizen of the Republic of Guatemala, residing at Oak Park, in the county of Cook and State of Illinois, have invented a new, original, and ornamental Design for a Combined Door Latch Handle and Mounting for Refrigerators or the like, of which the following is a specification, reference being had to the accompanying drawing, forming a part thereof.

Fig. 1 is a plan view of a combined door latch handle and mounting for refrigerators or the like, showing my new design.

Fig. 2 is a side elevation thereof.

Fig. 3 is an end elevation taken from the top of Figs. 1 and 2.

Fig. 4 is an end elevation taken from the bottom of Figs. 1 and 2.

I claim:

The ornamental design for a combined door latch handle and mounting for refrigerators or the like, as shown.

JOHN R. MORGAN.
